(57) CLAIM

The ornamental design for an ink bottle, as shown and described.

DESCRIPTION

FIG. 1 is a perspective view of an ink bottle showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front view thereof, shown without the cap for ease of illustration;

FIG. 9 is a rear view thereof, shown without the cap for ease of illustration;

FIG. 10 is a left side view thereof, shown without the cap for ease of illustration;

FIG. 11 is a right side view thereof, shown without the cap for ease of illustration;

FIG. 12 is a top view thereof, shown without the cap for ease of illustration; and,

FIG. 13 is a bottom view thereof, shown without the cap for ease of illustration.

The broken line portion shows unclaimed subject matter only and forms no part of the claimed design.
